Primary Examiner — Michelle E. Wilson*Assistant Examiner* — Messina L Smith(74) *Attorney, Agent, or Firm* — Quarles & Brady LLP;
James J. Aquilina(57) **CLAIM**

The ornamental design for an oral care device, as shown and described.

DESCRIPTION

FIG. 1 is a rear left perspective view of an oral care device showing my new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The dashed broken lines in FIGS. 1-7 show portions of the oral care device that form no part of the claimed design. The dashed-dotted broken lines in FIGS. 1-3, 6, and 7 show the boundaries of the claim and form no part of the claimed design. The relatively thin lines in the Figures show surface contours, not surface ornamentation.
